UNITED STATES PATENT OFFICE.

HARRY GRANT FRANCIS, OF RUSHVILLE, INDIANA.

ADHESIVE-SPREADER.

1,213,857.

Specification of Letters Patent. Patented Jan. 30, 1917.

Application filed March 29, 1915. Serial No. 17,725.

To all whom it may concern:

Be it known that I, HARRY GRANT FRANCIS, a citizen of the United States of America, and resident of 820 North Harrison 5 street, Rushville, in the county of Rush and State of Indiana, have invented certain new and useful improvements in Adhesive-Spreaders; and I do hereby declare the following to be a full and exact description 10 thereof, reference being had to the accompanying drawings, making a part of this specification.

My invention relates to adhesive spreaders and it has for its object the improvement in 15 construction of such devices whereby they are simplified and rendered more efficient in action.

The novelty of my invention consists in the combination and subcombination of the 20 parts as will be hereinafter set forth and specifically pointed out in the claims.

In the drawings Figure 1 is a front elevation of the adhesive spreader. Fig. 2 is a rear elevation of the upper portion of the 25 adhesive spreader. Fig. 3 is a section on line 3, 3, of Fig. 2. Fig. 4 is an end elevation showing arrangement of levers for operating sliding bar H.

In the drawings A, represents an adhesive 30 tank inclosed within an outer tank B, the space C between tanks A and B can be supplied with steam or hot water for heating the adhesive within the tank A. D is a perforated plate which is alternately sub- 35 merged within the adhesive or raised out of it when the machine is in operation.

E is a cover or lid which covers the adhesive when the perforated plate D is submerged within the adhesive. This cover E, 40 protects the adhesive from having dirt or any foreign matter falling into it. It also prevents the rapid oxidation and a scum 45 forming on top of the adhesive. Attached to the front edge near the middle lengthwise 50 of this cover E is a cord or chain F, which passes over grooved sheaves F², F³, which are pivoted to the standard F⁴ which is secured to the top of the tank A. One end of this cord or chain F is attached to an incline G. Two inclines are provided G and G² which are secured to a sliding bar H. A cord or chain I, is attached to one end of the sliding bar H. This cord or chain I passes over a grooved sheave I² and has its

opposite end from the bar H secured to a 55 lever K. This lever K has one end pivoted to a bracket K². Between the cord or chain I and the bracket K², the upper end of a connecting rod L is pivoted to the lever K, the lower end being pivoted to the arm M 60 which is secured to the shaft M²; this shaft turns in bearings within the legs B², B³, and the stand B³; attached to the shaft M² are arms M³, M⁴, which have their outer ends joined by a board M⁴. The arms M³, M⁴ 65 and the board M⁴ form a foot treadle to be used by the operator of the machine for turning the shaft M².

The perforated plate D is attached to the lower part of a vertically sliding bar D². 70 This bar D² is supported at its upper end by a stand N. The stand N, has cross bars N², and rollers N³ pivoted to it. The sliding bar D² is held in position by the cross bars N² and the rollers N³ and is free to move up 75 and down. The stand N has a vertical slot N⁴ through this slot a stud N⁵ which is secured to the sliding bar D², passes. A roller N⁶ revolves on this stud N⁵. Rollers N⁷, N⁷ 80 are placed in the lower part of the stand N on which the bar H, rolls. Angle pieces N⁸, N⁸, are secured to the foot of the stand N, to act as guides and hold bar H in position.

To operate the adhesive spreader the adhesive to be used must be placed in the tank A at such a depth that when the perforated plate D is at its lowest position it will be completely submerged within the adhesive, and when the plate D is at its highest position as shown in the drawings, the top of the plate D will be about one quarter of an inch above the top of the tank A. When the perforated plate D is at its lowest position, the lid E will be closed down on top of the 95 tank A.

The operation of my device is as follows: When not in use the lid E is always down on top of the tank A. The operator places his foot on the board M⁴, pressing it down; 100 this causes through the intervening mechanism the inclines G², G², to be pulled forward, raising the sliding bar D² and with it the perforated plate D and lid E. The perforated plate will be covered with the adhesive and the stock to be treated can have its edges rubbed over the plate and a sufficient amount of adhesive will adhere to the 105

stock to make a good joint, but no undue amount will be taken up causing a loss of the adhesive.

What I claim and desire to secure by Letters Patent is:

1. The combination in an adhesive spreader, of a tank, a perforated plate within the tank, vertical bars actuated by inclines for raising the plate, a tank cover operated by the bar that carries the inclines for operating the vertical bars.

2. The combination in an adhesive spreader of a tank, a perforated plate within the tank, vertical bars actuated by in-

clines for raising the plate, a tank cover operated by the bar that carries the inclines, the horizontal travel of the horizontal bar being greater than the vertical travel of the vertical bars.

3. The combination in an adhesive spreader of a tank, a plate within the tank, vertical bars actuated by inclines for raising the plate carried by a horizontal bar, a foot lever for operating the horizontal bar.

HARRY GRANT FRANCIS.
